(57) **CLAIM**

The ornamental design for a tub filler, as shown and described.

DESCRIPTION

FIG. 1 is a perspective view of a tub filler showing my new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken line showing of the spout opening, the bottom openings, and the extended arm of the tub filler represents unclaimed subject matter and forms no part of the claimed design.
